Primary Examiner — Lauren Calve(74) *Attorney, Agent, or Firm* — Parker Ibrahim & Berg LLP; Kenneth J. Heywood; Robert M. Amici(57) **CLAIM**

The ornamental design for a pill bottle with cap, as shown and described.

DESCRIPTION

FIG. 1 is a front perspective view of a pill bottle with cap showing our new design;

FIG. 2 is a front view thereof;

FIG. 3 is a rear view thereof;

FIG. 4 is a left side view thereof;

FIG. 5 is a right side view thereof;

FIG. 6 is a top side view thereof; and,

FIG. 7 is a bottom side view thereof.

The broken lines shown represent unclaimed subject matter and form no part of the claimed design.
